H. E. DELBARE.

RIBBON INKING ATTACHMENT FOR TYPEWRITERS.

APPLICATION FILED MAR. 30, 1921.

1,414,865.

Patented May 2, 1922.

Inventor:
Hector E. Delbare
By Jessie Rain Hinkle
J. H. H.

UNITED STATES PATENT OFFICE.

HECTOR E. DELBARE, OF CHICAGO, ILLINOIS.

RIBBON-INKING ATTACHMENT FOR TYPEWRITERS.

1,414,865.

Specification of Letters Patent. Patented May 2, 1922.

Application filed March 30, 1921. Serial No. 457,107.

To all whom it may concern:

Be it known that I, Hector E. DELBARE, a citizen of the United States, residing at Chicago, in the county of Cook and State of Illinois, have invented certain new and useful Improvements in Ribbon-Inking Attachments for Typewriters, of which the following is a specification.

The invention relates to ribbon inking attachment for typewriters.

One of the objects of the invention is to improve ribbon inking attachments for typewriters.

Another object is to provide a device that may conveniently be secured in place on a typewriter and as quickly and easily removed.

Another object is the provision of an improved ink distributing device.

Another object is to provide an improved and more convenient manner of supplying ink to the ink device without removing the device.

Another object is to provide an inking device which will not feed ink to the ribbon when the ribbon is not being moved.

Another object is the provision of an improved and convenient means for changing the character of ink of the inking device to suit the ribbon without removing the entire device, from the typewriter.

Another object is to conveniently and temporarily stop the inking operation of the attachment without removing it from the typewriter.

Another object is to provide an inking device by means of which a two-color ribbon may be inked at one time.

Another object is to provide an automatic ribbon inking device which continues to operate so long as the ribbon is fed through the typewriter during its ordinary use and which will not impose noticeable resistance to the normal operation of the machine.

Other, further and more specific objects of the invention will become readily apparent, to persons skilled in the art, from a consideration of the following description, when taken in conjunction with the drawings, wherein:

Fig. 1 is a plan view of the device as it

will ordinarily appear attached to typewriters of well known types.

Fig. 2 is a section taken on line 2—2 of Fig. 3, with the device turned in the opposite direction.

Fig. 3 is an elevation of the device.

Fig. 4 is a section taken on line 4—4 of Fig. 2.

Fig. 5 is an elevation of a felt-holding tube for containing a supply of ink to be subsequently applied to the ink distributing wheel.

Fig. 6 is a detail.

Fig. 7 is a view similar to Fig. 5 showing two elements serving as fountains for two different colored inks.

Fig. 8 is an elevation of a double, ink distributing roller, or wheel, for two different colored inks.

In all the views the same reference characters are employed to indicate similar parts.

The device consists of a rectangular tube 10 provided with angularly extending arms 11 and 12. Pivoted in the outer ends of the arms 11 and 12 is a distributing roller 13, having flanges 14 and 15 between which to receive a ribbon 16. The distributing roller 13 is held in place by a removable screw 17 which passes through the arm 12 and is threaded in the arm 11.

An arm 18 is pivoted to the rectangular tube 10, as at 19, and carries on its outer free end a roller 20, pivoted thereto by a screw 21 and held in contact with the distributing roller 13 by a spring 22. Between the pressure roller and the distributing roller the ribbon 16 is contained. 23 shows one of the spools of the ordinary typewriter upon which the ribbon is wound.

A rectangular fountain tube 25 slides freely in the rectangular tube 10 and carries an ink-absorbing felt strip 26. The tube 25 is closed at its rear end, as at 27, and carries a rearwardly projecting stem 28 which is screw threaded on its outer end, as at 29, for a finger knob 30. The fountain tube 25 has its upper wall slotted, as at 31, within which to introduce ink for saturating the felt strip 26. The tube 10 is provided in its upper wall with a series of perforations 32 which are in register with the slot 31 and through

which ink may be introduced into the slot for contact with the strip 26.

A spring holding tube 33 is provided on its inner end with a head 34 that bears against the rear end of the tube 25. It has an enlarged end 35 which projects on the outside of the tube 10. Around the tube 33 is wound an open, helical compression spring 36 which has one of its ends bearing against the head 34 and the other end bearing against the end wall 37 of the tube 10. The spring 36 yieldingly holds the front end of the ink feeding felt strip 26 in contact with the ink distributing roller 13.

15 Tube 10 is axially slotted in one of its side walls, as at 38, and tube 25 bears an outwardly projecting pin 39 that moves in the slot 38 when the tube 25 is axially moved by contact with the handle or knob 30. A 20 latch 40 is pivoted to the tube 10, as at 41, and carries a detent 42 on its free end for engagement with the pin 39, to hold the end of the felt strip 26 out of contact with the ink distributing roller 13, so that the 25 device may thus be prevented from distributing ink to the ribbon 16 when desired.

Fig. 7 shows two parallel tubes 25 and 25' in one that may be placed in tube 10, so that both black and red ink, or other different colored inks, may be fed to a two-color ribbon, and Fig. 8 shows a double ink distributing roller, consisting of the rollers 13 and 13', separated or in one, adapted to distribute ink of different colors to a ribbon 35 bearing corresponding colors.

When a single tube 25 is used and it is desired to change the character of the ink, it is only necessary to remove the screw 17 and take away the distributing roller 13, 40 whereupon the tube 25 may be taken from the tube 10 after the knob 30 has been unscrewed, so as to permit the stem 28 to pass freely through the tube 10 and the tube 33 contained therein, whereupon another tube 45 25, bearing a different character of ink, may be substituted and a different distributing roller 13 may be inserted in the place of the roller taken from the device, so that to change ink to suit the ribbon it is only necessary to change the tube 25 and the roller 50 13 without removing the entire device from the machine.

A cover plate 43 is pivoted, as at 44, to the tube 10 and normally overlies and covers 55 the perforations 32 to prevent entrance of dust to the felt distributing strip 26.

45 represents a part of the frame of a typewriter to which the device as a whole may attachably be connected by means of 60 the thumb screws 46 and 47. The outer tube 10 is connected to a plate 48, as at 49, and the plate carries strips 52 and 53 having on one end flanges 50 and 51, and on the other end screws 46 and 47. When it 65 is desired to remove the device from the

typewriter it is only necessary to loosen the screws 46 and 47 and to remove the ribbon 16 from between the pressure roller 20 and the distributing roller 13.

When the ribbon is moved in the ordinary 70 use of the typewriter, the ink distributing roller 13 is thereby rotated because the roller 20 yieldingly holds the ribbon in contact therewith and the thin film of ink that has been deposited upon the roller 13 from the 75 inking strip 26 is taken up and absorbed by the ribbon. Not any more ink than is deposited upon the roller 13 can be absorbed by the ribbon and therefore when the ribbon 16 is standing still, it is not supersaturated as it would be if it were directly in contact with the ink-laden strip 26.

'The attaching means for different types of typewriters may be modified to suit the style of the machine.

Fig. 7 shows in a single structure two fountain tubes in which the ink feeding strip 26 may be shorter than strip 26' so that the latter may be "inked" through slots 31' without removing the structure 90 from tube 10.

The ink distributing roller 13 may be made in two separate parts or separated by a circumferential groove and made in a single piece.

While I have herein shown a single embodiment of my invention for the purpose of clear disclosure, it will be manifest to persons skilled in the art, that many changes may be made in the general configuration and disposition of the parts within the scope of the appended claims.

Having described my invention what I claim as new and desire to secure by Letters Patent, is:—

1. An automatic ribbon inking attachment for typewriters comprising an ink distributing roller; a spring-pressed pressure roller for yieldingly holding the ribbon in contact with the distributing roller to rotate the latter as the ribbon is intermittently moved; an axially movable tube containing an ink absorbing element yieldingly held in contact with the distributing roller and a spring to hold said element in contact with the distributing roller for distributing ink on the ribbon.

2. An automatic ribbon inking attachment for typewriters comprising a rotatable ink distributing roller; a pressure roller; a spring to move the pressure roller for yieldingly holding the ribbon in contact with the distributing roller to rotate the latter as the ribbon is moved; a tube movable axially toward the distributing roller; an ink absorbing element in the tube normally in contact with the distributing roller and means for yieldingly holding said element in contact with said roller.

3. An automatic ribbon inking attach-

ment for typewriters comprising an ink receptacle; an ink conveying element extending therefrom; an ink distributing roller normally in contact with said element; 5 yielding means for holding the said ribbon in contact with the ink distributing roller, whereby to rotate the latter to apply ink to the ribbon by movement of the ribbon and a latch to alternatively hold the ink conveying element out of contact with said ink distributing roller. 10

In testimony whereof I hereunto subscribed my name.

HECTOR E. DELBARE.
